UNITED STATES PATENT OFFICE

AUGUST B. BLOME, OF ST. GEORGE, NEW YORK, ASSIGNOR TO THE SUPERHEATER COMPANY, OF NEW YORK, N. Y.

WATER TUBE FIRE-BOX BAFFLE

Application filed May 10, 1930. Serial No. 451,333.

My invention relates to baffles for fire-boxes and to the combination of a water tube baffle and a fire-box. I aim to provide a baffle giving a relatively long travel to the gases in a fire-box and relatively low maintenance costs.

5 In order that my invention, together with further objects and advantages, may be clearly understood, I will now describe in detail in connection with the accompanying drawings a particular fire-box containing a baffle embodying my invention, the arrangement of 10 the baffle in the fire-box being also within my invention. In said drawings,

Fig. 1 is a longitudinal sectional view on a 15 vertical plane through a fire-box and baffle taken on the line 1—1 of Fig. 2 looking in the direction of the arrows;

Fig. 2 is a transverse sectional view of the 20 fire-box illustrated in Fig. 1 taken on a vertical plane and looking toward the right of Fig. 1; Fig. 3 is a sectional plan view taken on the line 3—3 of Fig. 2.

The apparatus illustrated in the drawings 25 comprises the fire-box end of a particular type of high pressure, water tube locomotive boiler. However, it will be understood that in its broader aspects my invention is not limited to high pressure boilers, water tube boilers, or to locomotives.

30 Referring more particularly to the drawings, the known features of the construction illustrated comprise a boiler having a central top drum 10 and two smaller drums 12, 12 at a somewhat lower level than the drum 10 and which form the upper longitudinal corners of a fire-box chamber 14. The chamber 14 is illustrated as having side walls formed of two sets of water tubes 16, 16 and 18, 18, the upper ends of which connect 35 into the drums 12, 12 and the lower ends of which connect into a hollow foundation ring 20. It will be seen that the tubes 16 have their upper and lower ends on the same side of the longitudinal center of the chamber 14 40 while the tubes 18 bend sharply across the

top of the chamber 14 near the drums 12 and have their upper ends on the opposite side of chamber 14 from their lower ends. Water is supplied to the foundation ring 20 by down-comers 22 running between the drums 12 and the ring 20 on the outsides of tubes 16 and 18 and also by circulators 24, 24 between the lower corner drums 26, 26 of the boiler and the transverse forward section 20a of the ring 20.

50 The fire chamber 14 will be understood to have a grate or burner below or at the level of the ring 20 and that the gases of combustion pass upwardly to chamber 14 through an aperture formed by ring 20 and discharge from the chamber 14 at the forward end thereof above the transverse portion 20a. It is common to provide in fire-boxes of this type baffling means to increase the length of the path of the gases in the fire-box, such 55 baffling means commonly comprising arch tubes supporting refractory blocks forming a baffle. The baffling means in accordance 60 with my invention comprises a series of water tubes, the lower portions of which are set 65 close together and extend in a line across the forward end of the fire-box, such tubes inclining rearwardly of the fire-box and bending upward and laterally of the fire chamber, but being of different lengths so that they 70 connect into the longitudinal wall of the fire chamber at points spaced longitudinally of the fire-box whereby ample space is provided 75 for the passage of the combustion gases through the upper ends of the tubes. As 80 illustrated, my improved baffle comprises tubes 28, 28 of the bifurcated type whose lower ends connect into the transverse foundation member 20a by means of throats 29 and which bifurcate a short distance above member 20a. 85 The upper ends of the tubes 28, however, do not reunite, but the two tubes 28 rising from a given throat 29 at the level of the member 20a connect into a drum 12 at longitudinally 90 spaced points. This arrangement has been

adopted to provide a pathway of large cross section for the gases through the upper ends of tubes 28. In order to provide a passage of maximum area for the gases of combustion while also obtaining a long average path of travel of the gases within the fire-box, the following particular arrangement has been adopted:

The tubes 28 lying on each side of the center of the transverse member 20a are divided into two groups. The tubes in the group nearest the side of the fire-box are numbered from 101 to 106 beginning with the tube nearest the side of the fire-box. The group of tubes adjacent the center of the cross member 20a is numbered from 107 to 112, respectively, beginning with the tube nearest the side of the fire-box. Each tube 101 is connected into the drum 12 on its side of the chamber 14 at a more forward point than any other tube of its group. The tubes 102 to 106 inclusive are connected into the drum 12 on their side of the fire chamber 14 at points along its length successively nearer the rear of the fire-box. As appears in Fig. 2, tubes 101 to 106 inclusive are all bent laterally at their upper ends so as to connect into drum 12 along a given longitudinal element of the drum, the tubes of a group defining a warped surface whose trace on the drum 12 is parallel to the central longitudinal axis of the fire chamber 12. As shown, outside tubes 101 and 102 bend first away from the sides of the fire-box and then towards them. Tubes 107 to 112 inclusive are treated similarly to tubes 101 to 106, tubes 107 entering drum 12 substantially at the same distance from the rear of the drum as tubes 101 but higher up on the drum, so that, as appears in Fig. 1, tubes 107 almost overlie tubes 101 when viewed from the center of the fire-box. Similarly, tubes 108 to 112 inclusive connect into drums 12 at substantially the same distances from the ends of the drum as tubes 102 to 106 inclusive. However, as appears from Fig. 2, tubes 107 to 112 inclusive connect into drums 12 along given longitudinal elements of the drums 12 parallel to but somewhat inside and above the ones along which tubes 101 to 106 connect with the drums so that the inner groups of tubes also define warped surfaces.

While I have described tubes 28 as being of the bifurcated type, I do not limit myself to this or to any other detail of the disclosure herein except insofar as such detail is clearly and positively included in one of the appended claims. In particular, it will be understood that tubes having reduced ends may be substituted for bifurcated tubes within the broader of the claims. Also tubes of constant size but staggered at their points of connection to the foundation ring may be used in place of the bifurcated tubes 28. Furthermore, I do not limit myself to a baffle extending entirely or continuously across the fire-

box, as I may omit tubes at the side of the fire-box or at intermediate points in the baffle as desired.

I claim:

1. The combination in a fire-box of longitudinal water-containing means in the upper portion of the fire-box, a transverse water containing member in the lower portion of the fire-box, water tubes arranged in groups transversely of the fire-box and having their lower ends connected into said member and having their lower portions set close together to form a baffle, the tubes of one group having their upper portions spaced apart and connected into said means along lines parallel to the central longitudinal axis of the fire-box and the tubes of another of said groups having their upper ends spaced apart and connected into said means along lines parallel to the lines along which said first mentioned groups are connected to said drums but at higher levels thereon.

2. The combination in a fire-box of a hollow foundation member, means forming a water space in the upper portion of the fire-box extending longitudinally thereof, water tubes connected into said member at their lower ends along a line transversely of the fire-box and having their lower portions set close together to form a baffle but having their upper portions spaced apart and bent to permit passage of gases therebetween said baffle forming tubes being arranged in groups, the tubes of the groups nearer the sides of the fire-box defining surfaces whose traces on the drums lie below and outside of the traces on the drums of the surfaces of the inner groups of tubes.

3. The combination as set forth in claim 1 and in which the two groups of tubes connect into the longitudinal water containing member within zones whose ends are substantially the same distances from an end of the box.

4. The combination in a firebox having a gas outlet at one end, of means forming a water space along the upper longitudinal corners of the firebox, a transverse water containing member forward of the lower portion of the fire-box, and water tubes connected into said member at their lower ends and inclined upwardly and rearwardly from the gas outlet of the fire-box, said tubes having their lower portions close together to form a baffle and having their upper ends connected into said means at longitudinally spaced points whereby the upper portions of the tubes are separated to provide a passage-way for the gases to the outlet, said water tubes being arranged in pairs, the tubes of each of said pairs having at their lower ends a common throat for connection into the transverse water containing member and being separated at their upper ends.

5. A boiler having in combination longitudinally extending drums at the lower cor-

ners of its transverse cross section, a water tube fire-box extending rearwardly from said drums and having a foundation member including a transverse portion adjacent but lower than the rear ends of said drums, water tubes connected into said transverse portion and extending upwardly, rearwardly and laterally therefrom and having outlet connections therefrom at their upper ends, and 10 water supplying connections from said drums to said transverse portion.
